DRAG BIT

John E. Eckel and Everett H. Lock, Tulsa, Okla., assignors, by mesne assignments, to Esso Products Research Company, a corporation of Delaware

Filed Dec. 19, 1963, Ser. No. 77,859

Term of patent 3½ years

(Cl. D54—4)

FIG. 1

FIG. 2

FIGURE 1 is a front elevational view of a drag bit showing our new design; and

FIGURE 2 is a bottom view of the drag bit shown in FIGURE 1.

We claim:

The ornamental design for a drag bit, substantially as shown.
